Primary Examiner — Jeffrey D Asch*Assistant Examiner* — Tracey J Bell(74) *Attorney, Agent, or Firm* — Goodwin Procter LLP(57) **CLAIM**

The ornamental design for a cleat for a article of footwear, as shown and described.

DESCRIPTION

FIG. 1 is a plan view of a cleat for an article of footwear showing my new design;

FIG. 2 is a forward perspective of a lateral side view thereof;

FIG. 3 is a lateral side view thereof;

FIG. 4 is a rear perspective of the lateral side view thereof;

FIG. 5 is a forward perspective of a medial side view thereof;

FIG. 6 is a medial side view thereof;

FIG. 7 is a rear perspective of the medial side view thereof;

FIG. 8 is a rear view thereof; and,

FIG. 9 is a front view thereof.

The broken lines illustrate portions of the cleat for article of footwear that form no part of the claimed design.

1 Claim, 8 Drawing Sheets(56)
